THREAD GUIDE AND SUPPORT THEREFOR

Carlyle Herbert Wainwright, Tom Leslie Mountain, and Frederick Edward Deans, Leicester, England, assignors to The Bentley Engineering Company Limited, Leicester, England, a British company

Application November 26, 1938, Serial No. 242,609
In Great Britain December 9, 1937

4 Claims. (Cl. 242—157)

This invention is for improvements in or relating to thread-handling devices which are applicable for use in connection with knitting machines, but which are also applicable for use in other machines in which a thread or threads is or are to be dealt with.

The invention is particularly concerned with thread-guides of a type commonly known by the term "pot eyes." A pot-eye is a short tube of porcelain or like material having a highly glazed surface, and such eyes are usually fixed in position in a supporting bracket by means of thermoplastic material which becomes plastic at a temperature higher than ordinary temperatures.

15 It is usual for a pot-eye to be formed with a main barrel portion which at one end continues into an enlargement having a slightly flared mouth the surrounding margin of which is of smooth or rounded form over which the thread 20 can be traversed without damage to the thread.

An object of the present invention is to provide an improved means for fixing such pot-eyes in their brackets or supports.

According to the present invention a support for 25 a pot-eye comprises a plurality of radial blades or spring fingers which surround an aperture in the bracket into which the pot-eye is to be inserted and which extend to an imaginary circle which has a diameter slightly less than that of the 30 barrel portion of the pot-eye.

Thus, when the pot-eye is inserted in the aperture by pressure against the extremities of the blades or fingers from one side of the aperture, the blades or fingers spring slightly in the direction in which the pot-eye is pushed with the result that although but little force is required to 35 insert the pot-eye between the ends of the blades, the blades resist withdrawal of the pot-eye from the aperture since the barrel portion of the pot-eye prevents their return to their original position.

Preferably, the ends of the blades are bent in the general direction in which the pot-eye is inserted, that is to say, each blade extends first 40 radially and then axially of the aperture which receives the pot-eye. This formation of the blades has been found convenient in cases where the diameters of the barrels of the pot-eyes are found to vary somewhat between different pot- 45 eyes.

In order that the invention may be more clearly understood two examples will now be described with the aid of the accompanying drawing, in which

50 Figure 1 is a sectional elevation through a sup-

port for a pot-eye in a plane containing the axis of the aperture through which the pot-eye is to be inserted, and is a section on the line 1—1 of Figure 2, looking in the direction of the arrows;

Figure 2 is a section on the line 2—2 of Figure 1 looking in the direction of the arrows, and

Figures 3 and 4 are views respectively similar to Figures 1 and 2 of a modified form of pot-eye.

Like references indicate like parts throughout the several figures of the drawing.

Referring to Figures 1 and 2, a bracket 10 is formed with an aperture 11 surrounding which the material of the bracket is formed into a number of inwardly projecting radial fingers 12 spaced from one another around the axis of the 15 aperture 11. The inner ends 13 of these blades normally extend to an imaginary circle which has a diameter slightly less than the barrel portion of the pot-eye 14 which, in Figure 1, is shown alongside the bracket where it can be clearly 20 seen that the diameter of the barrel is slightly larger than the diameter of the imaginary circle to which the inner ends 13 of the blades extend. When the pot-eye is forced or inserted into the aperture 11 by movement to the right in 25 Figure 1, the blades will spring slightly in the direction in which the pot-eye is pushed as indicated in dotted lines, the barrel portion of the pot-eye being also indicated in dotted lines as inserted within the embrace of the fingers of 30 the blades. The result is that although but little force is required to insert the pot-eyes the blades press against the surface of the barrel in a direction to prevent withdrawal of the pot-eye since the barrel portion of the pot-eye prevents return 35 of the blades into their normal position.

In an alternative construction as illustrated in Figures 3 and 4 six blades 12' are employed in place of the four blades 12 of Figures 1 and 2, and the ends of the blades are bent initially in 40 the general direction in which the pot-eye is inserted and these blades are shown in Figure 3 only in their initial position although the barrel of the pot-eye is shown in dotted lines to indicate its relative diameter with respect to the extension of the inner ends 13' of the blades to the imaginary circle aforesaid. In other words, each blade extends first radially and then axially of the aperture 11' of the bracket 10'.

This second construction is found to be preferable in the case in which the diameters of the barrels of the pot-eyes vary somewhat between one pot-eye and another.

We claim:

1. A thread-handling device comprising in 55

combination a pot-eye comprising a barrel and an enlargement at one end thereof, and a support for the pot-eye which latter has an aperture surrounding the pot-eye and has a plurality of radial blades each of which first extends from the margin of the aperture substantially radially towards the center thereof and near its free end is bent over to extend axially of the aperture away from the enlargement of the pot-eye, the ends of the blades terminating on the barrel of the pot-eye and gripping the same resiliently.

2. A thread-handling device constructed in accordance with claim 1 and having the blades and at least that portion of the body of the support immediately surrounding the aperture formed in one from a single piece of material.

3. A thread-handling device constructed in ac-

cordance with claim 1 in which the blades extend from the margin of the aperture towards their free ends as smoothly curved members.

4. Brackets for supporting pot-eyes each comprising a flat support of resilient metal having an aperture for reception of a pot-eye of dimensions substantially larger than the transverse dimensions of the pot-eyes, spring blades extending inwardly from the edges of the aperture, which blades are bent to extend also axially of the aperture and terminate at an imaginary circle of a diameter slightly smaller than a pot-eye so that on insertion of a pot-eye the blades will be sprung outwardly and will grip the pot-eye resiliently.
